UNITED STATES PATENT OFFICE

GEORGE G. GOING, OF STAMFORD, CONNECTICUT, ASSIGNOR TO REMINGTON TYPE-
WRITER COMPANY, OF ILLION, NEW YORK, A CORPORATION OF NEW YORK

TYPEWRITING MACHINE

Application filed June 5, 1929. Serial No. 368,539.

My invention relates to typewriting machines and more particularly to means associated with the escapement mechanism and controlling means therefor.

5 One of the main objects of my invention, generally stated, is to provide simple, light, compact, inexpensive and effective means for controlling the escapement mechanism, which means occupies but little space, is, nevertheless, reliable in use and is not apt to be injured or broken.

10 Another object of the invention, generally stated, is to provide simple and effective line lock mechanism operating in conjunction with said controlling means.

15 A further object of my invention is to provide simple and effective means whereby a printing key may be actuated and control the escapement to advance the carriage even though the space key be held depressed, and whereby the space key may be actuated to advance the carriage even though a printing key be held depressed.

20 A still further object of my invention is to provide means for automatically breaking or rendering ineffective the connections between the space key and the escapement mechanism when the line lock mechanism is operated to lock the type actions against printing operation.

25 Another object of the invention is to provide means of the character specified which are noiseless, or substantially noiseless in operation.

30 Another object of the invention is to provide simple, light, compact and comparatively inexpensive mechanisms of the character specified which may be embodied in a small portable typewriting machine without adding appreciably to the weight thereof and without unduly crowding or interfering with other features of the construction.

35 A still further object of the invention is to provide adjustable means for regulating the operation of the parts.

40 To the above and other ends which will hereinafter appear my invention consists in the features of construction, arrangements of parts and combinations of devices set forth in

the following description and particularly pointed out in the appended claims.

In the accompanying drawings, wherein like reference characters designate corresponding parts in the different views,

45 Fig. 1 is a vertical, central, fore and aft sectional view of the machine with some of the parts shown in side elevation.

Fig. 2 is an enlarged, detail, fragmentary, vertical, fore and aft sectional view taken through the rear portion of the machine.

50 Fig. 3 is a fragmentary, bottom plan view showing the escapement mechanism and some of the associated parts.

Fig. 4 is a detail, skeletonized, perspective view showing the line lock mechanism and some of the associated parts.

55 Figs. 5 and 6 are detail, fragmentary perspective views showing modified forms of cushioning means for the trip-off device controlled by the space bar.

60 I have shown my invention, in the present instance, embodied in a noiseless portable machine of the character disclosed in my application Serial No. 331,534, filed Jan. 10, 1929 in which the devices of the present invention may be readily incorporated without modifying, or materially modifying other structural features of said machine. It should be understood, however, that the invention is not 65 restricted in its use to any particular character of typewriting machine but may be employed in such machines generally, wherever found available. The nature of the invention, from certain aspects, is such, however, as to render it particularly available for use in portable typewriting machines.

70 In the accompanying drawings I have shown only so much of the said noiseless portable typewriting machine referred to above as is necessary to arrive at an understanding of my present invention in its embodiment therein.

75 Other features of the machine referred to above are disclosed in the following applications filed by me:

Serial No. 363,757 filed May 17th, 1929

Serial No. 364,038 filed May 18th, 1929

Serial No. 365,426 filed May 23rd, 1929

(now patent No. 1,767,877, dated June 24, 1930)

Serial No. 365,885 filed May 25th, 1929

Serial No. 366,623 filed May 28th, 1929

5 (now patent No. 1,767,878, dated June 24, 1930)

Serial No. 367,733 filed June 1st, 1929

10 The frame of the machine is constructed as disclosed in my application Serial No. 365,885, and comprises side plates 1 united by castings 2, 3, and 4 by which various working parts of the machine are supported.

15 The noiseless type actions shown in the present instance are the same as those disclosed in my aforesaid application Serial No. 331,534 and comprises type bars 5 pivoted at 6 and each controlled by toggle links or members 7, 8, 9 and 10, each toggle link 9 having a weighted member 11 connected thereto. Each type bar is provided at the heel thereof with teeth 12 meshing with teeth 13 on a slide 14. Each slide 14 is pivoted at its forward end to one arm of a sub-lever 15 pivotally supported on a hanger 16. The hangers 16 are supported on a plate 17 which in turn is secured to the casting 3. Each sub-lever has an arm thereof pivoted to a depending link 16 that loops under an associated key lever 17 provided with a finger key 18. Each 20 type action is restored to normal position by an associated contractile spring 19.

25 A contact portion 20 on the heel of each type bar coacts with a segmental universal bar 21 as a type bar approaches the printing position and actuates said universal bar to operate the carriage escapement mechanism, as will hereinafter more clearly appear. The universal bar is of yoke-like formation with parallel side arms pivoted at 22 to bracket 30 arms 23 supported by the casting 3. A depending arm 24 on the universal bar is pivoted to one end of a link 25, the rear end of said link being pivoted to one arm of an angular lever 26 pivoted at 27 to an arm 45 of a bracket 28 fixed to the carriage support, designated as a whole by the reference numeral 29. The rear arm of the lever 26 carries an adjustable contact screw 30 which coacts with a dog rocker 31 pivoted at 32 on arms 50 of the bracket 28. The dog rocker 31 carries feed dogs 33 and 34 which coact with an escapement wheel 35 supported to turn in a bearing in the bracket 28 and arranged beneath the carriage support 29. The escapement wheel is fixedly connected to a feed pinion 36 that meshes with a feed rack 37 carried by the carriage. Said feed rack is pivoted at 38 to depending bracket arms 39 that are secured to the end plates 40 of the carriage.

60 An arm 41 is secured to the feed rack 37 and terminates in a finger piece 42 by which the feed rack may be swung on its pivots 38 into and out of mesh with the feed pinion 36.

65 The carriage comprises the end plates 40,

mentioned above, which are secured to a cross bar 43 provided with oppositely disposed raceways 44 in which crossed anti-friction rollers 45 are received. These rollers also are received in oppositely disposed raceways 46 70 in the carriage support 29. A cylindrical platen 47 is supported in bearings in the end plates 40 of the carriage. A spring drum 48 is supported on the carriage support 29 and has one end of a cord (not shown) connected 75 thereto, the other end of said cord being affixed to the carriage.

The carriage support 29 may be mounted for up and down case shifting movement on the rear casting 4 as disclosed in my above 80 mentioned applications Serial Nos. 365,426 and 366,623. For the purposes of the present invention I do not deem it necessary to illustrate such means for mounting and effecting a case shifting movement of the carriage support, it being sufficient to bear in mind that the rear end of the link 25 is moved up and down with the carriage support when the latter, together with the carriage and other parts carried thereby, are given case shifting movements; that the connections between the universal bar 21 and the feed dogs is not effectively altered whether the platen be in the upper or lower case position, and that the correlation between the escapement wheel, 90 the feed dogs, the spring drum, the feed rack, feed pinion and the carriage etc. is not in any way altered whether the platen be in the upper or lower case position.

95 In order to further guide and support the 100 carriage I have extended the rear casting 4 up in the rear of the platen as indicated at 4^a, it being understood that this casting constitutes the rear of the frame of the machine. The upward extension 4^a of this casting has 105 an inclined guide plate 49 secured thereto. A cross bar 50 is connected at its ends to and unites the end plates 40 of the carriage. The rear edge of this cross bar bears against the front face of the guide plate 49 and resists, 110 in the rear of the printing point, the pressure of the type bars against the platen. Suitable connections as fully disclosed in my application Serial No. 365,426 (now Patent No. 1,767,877), are provided to maintain the rear 115 edge of the cross bar 50 against the guide plate 49 without, however, interfering with the up and down and longitudinal sliding movement of the bar 50 on the face of the guide plate. It is unnecessary to describe in 120 detail such means herein, the general purpose of the connection being understood.

The control of the escapement mechanism from all of the printing keys is effected by the heel of the actuated type bar operating 125 the universal bar 21 and transmitting motion therefrom through the link 25 to the angular lever 26. This results in moving the dog rocker 31 and a letter feed advance of the carriage is effected at the down stroke of the 130

printing key. It should be understood, however, that, preferably, the let-off of the carriage does not take place until after the depression of the printing key has been arrested by a padded stop 51 with which all of 5 the printing key levers coact. As fully explained in my application Serial No. 331,534 this arrest in the depression of the key lever takes place before the associated type bar reaches the platen, the pressure imprint being effected by a continued movement of the 10 weighted part 11, the type bar and other parts of the type action independently of the companion key lever. It results from this construction that if the operator should maintain a printing key depressed this will not 15 result in holding the dog rocker in its actuated position. If, therefore, at this time the universal bar should be actuated from the space key by an independent train of connections, then the carriage would be advanced 20 by the space key even though a printing key is held depressed. I have provided such an independent train of connections from the space key to the universal bar, the character 25 of which also permits an actuation of the printing keys to advance the carriage even though the space key be maintained depressed. Such construction will now be described.

30 The space key 52 is supported by rearwardly extending arms 53 connected at their rear ends to a rock shaft 54 which is square in cross section. A rearwardly projecting arm 55 is secured to this shaft and has pivoted thereto at 56 a trip-off device designated as a whole by the reference numeral 57. In the present instance this so-called trip-off device consists of an angular lever having a forwardly extending arm 58 and an upstanding arm 59. A contractile spring 60 is connected at one end to the arm 55, as indicated at 61, whereas the other end of said spring is connected to an ear 62 on the bottom of the trip-off device. The force of the spring 60 tends 40 to turn the device 57 on its pivot 56 in a clockwise direction, as the parts are viewed in Fig. 4. A suitable buffer or cushioning device is employed that stands in the path 45 of the upright arm 59 of the trip-off device to noiselessly arrest said device when it is returned to normal position under the action of its spring 60. I have shown several forms 50 of cushioning devices that may be employed for this purpose. That shown in Fig. 4 is in the nature of a closely wound coiled spring 63 that surrounds a sheet metal supporting arm 64. The spring is confined on said arm 55 between a pin 65 carried at the outer end thereof and a washer 66 supported on the arm and bears against a shoulder thereon. The rear edge of the upright arm 59 normally 60 rests against the spring 63 so that the upper flat end of said arm underlies an off-set

lug or ear 67 on a rearwardly extended arm 68 on the universal bar 54.

An adjustable stop 69 is interposed in the path of the arm 58 of the trip-off device so as to coact therewith at the last portion of the 70 depression of the space key. The effect of thus arresting the arm 58 is to cause the trip-off device to turn on its pivot 56 and move the arm 59 forward, thereby releasing it from the lug 67 and freeing the universal bar for 75 independent return movement under the action of a returning spring, not shown. This break in the train of the operative connections between the space key 52 and the universal bar 21 takes place immediately after the dog 80 rocker has been rocked a distance sufficient to bring about a letter space advance of the carriage. Therefore, the universal bar 21 will return to normal position ready to be actuated by the operation of a printing key even 85 should the operator maintain the space key is depressed. When the depressed space key is released the trip-off device 57 will be lowered, the arm 59 thereof first sliding down the front 90 face of the lug 67 when released from the restraint of the stop 69 and when the top end of the arm 59 clears the lug said arm will turn back to and be arrested by the cushion stop 63.

95 Any suitable stop may be employed in place of the stop 69. However, the construction shown is simple and effective for the purpose set forth, and comprises a disk-like stop member 69 secured to a depending bracket arm 70 by a headed clamping screw 71, the threaded stem of which passes through an eccentrically disposed hole pierced in the stop 69. The threaded end of the screw engages a tapped opening in the bracket arm. A tightening of 100 the screw 71 clamps the eccentric in its adjusted position. The rotative adjustment of the stop presents a peripheral stop surface higher or lower and arrests the arm 58 sooner or later in its movement thus determining the 105 point in the depression of the space key when the break in the train of connections shall take place.

110 In the construction shown in Fig. 5 the arm 59 of the trip-off device normally rests against a pad 72 of felt or like material secured to the end of an arm 73.

115 In the construction illustrated in Fig. 6 the upper end of the upright arm 59^a of the trip-off device 57^a carries a pad 74 of felt or like material that normally bears against the lug 67 on the universal bar. A shoulder 75 on the arm 59^a normally underlies the lug 67 on the universal bar. An arm 76 is arranged in the rear of the arm 59^a and is normally out 120 of contact therewith and is employed for purposes which will hereinafter appear.

125 In accordance with my present invention I employ a line lock mechanism which is simple in construction and operates to lock the universal bar against actuation by the 130

type bars and prevent a printing operation of the latter. Such line lock mechanism is also combined with the trip-off mechanism described above to break the train of connections between the space key and the universal bar in order that the parts will not be strained, injured or possibly broken, by attempting to actuate the space key when the universal bar is locked. By breaking the train of actuating connections between a key (the space key in the present instance) and the line locked part (the universal bar in the present instance) no force can be exerted on the locked part and no injury thereto can result. From certain aspects of my invention I contemplate broadly the provision of such means.

The line lock mechanism includes an upright lever 78 pivoted at 79 on a rock shaft 80 supported in bearings in the casting 4. The upper end of the lever 78 is bent forward at 81 and normally extends into the path of travel of a stop or line lock abutment 82 carried by and adjustable to different positions along a stop bar 83 carried by the carriage. One end of the rock shaft 80 has a crank arm 84 secured thereto. A forwardly extending link 85 is pivoted at its rear end to said crank arm 84 and at its forward end is pivoted to one arm of a bell crank lever 86. A stem 87 that carries a release key 87 is pivoted to the other arm of the bell crank for actuating it and through the intermediate train of connections effect a rocking of the shaft 80. This results in moving the end 81 of the lever 78 out of the path of the stop 82 and releasing the line lock as will presently appear.

The lower end of the lever 78 is bifurcated at 88 to straddle the rear end of a horizontally disposed line lock lever 89 pivoted, at 90, to a forwardly projecting arm 91 on the casting 4. The forward end of the lever 89 is adapted to move to a position beneath, and into and out of the path of, a lug or ear 92 on the universal bar 21. When the lever 89 is under said lug the universal bar is locked against movement, or against movement a sufficient distance to permit a type bar to reach printing position and to enable the universal bar to actuate the escapement mechanism to advance the carriage a letter space distance. Should the operator, at this time, desire to add one or more letters to complete a word or to insert a hyphen a depression of the release key 87 will, as previously pointed out, clear the upper end of the lever 78 from the line lock stop 82, enabling a spring 93 to return the levers 78 and 89 to normal position. When the operator releases pressure from the depressed release key 87 a spring 94 will restore the rock shaft 80 to normal position, bringing the upper end of the lever 78 into path of the stop 82 ready for the next line locking operation.

Extending to the right from the line locking lever 89 is an arm 95 which terminates

in the supporting arm 64 on which the cushion stop 63 is mounted. It will be understood that when the forward end of the line lock lever 89 is moved to a position beneath the lug 92 on the universal bar, the arm 95, 64 will be moved forward. This will result in rocking the trip-off device 57 around its pivot 56 and carrying the upper end of the arm 59 forward from beneath the lug 67 on the universal bar. The result is that the train of connections between the space key 52 and the universal bar is broken or rendered ineffective, so that any pressure exerted on the space key at this time will not be exerted on the locked universal bar and none of the parts intermediate the space key and the locked part (the universal bar in the present instance) is subjected to any strain, such as would result from an attempt to operate the space key when an unbroken train of connections therefrom to the locked part is employed.

It will be understood, of course, that when the line lock is released either by an actuation of the release key 87 or by returning the carriage to the right, the arm 95, 64, will be returned to normal position and permit the trip-off lever 57 to resume its normal position with the upper end of the arm 59 thereof beneath the lug 67, ready to actuate the universal bar on the depression of the space key.

The operation of the construction disclosed in Fig. 5 is the same as that described above.

In the construction disclosed in Fig. 6 the arm 76 moves forward when the line lock lever 89^a which carries it is moved to the locked position, thereby moving the trip-off device 57^a to a position where the shoulder 75 thereon will be displaced from beneath the lug 67, holding the trip-off device thus disengaged until the line lock lever is shifted back to normal position.

The distance of the arm 76 from the upright arm 59^a, as the parts are normally disposed, is somewhat exaggerated in Fig. 6 in order that it may be made to clearly appear that the arm 76 is out of contact with the arm 59^a in the normal condition of the parts and are only brought into contact when the line lock lever 89^a is shifted to lock the type bars and break the train of connections between the space key and the universal bar.

From the foregoing description it will be seen that I have provided a simple, compact, efficient and noiselessly operating construction for attaining the ends pointed out.

Various changes may be made in the construction, and parts thereof may be employed without others, without departing from my invention as it is defined in the accompanying claims.

What I claim as new and desire to secure by Letters Patent is:

1. In a typewriting machine, the combination

tion of a carriage, escapement mechanism therefor, a universal bar for actuating said escapement mechanism, type actions operative on said universal bar, a space key, and independent train of operative connections 5 between said space key and said universal bar, and means operating automatically when the carriage reaches the end of a line for effecting a relative displacement between parts of said connections and thus rendering 10 said space key ineffective to actuate the escapement.

2. In a typewriting machine, the combination of a carriage, escapement mechanism therefor, type actions, means for actuating 15 the escapement mechanism by an operation of any of said type actions, line lock mechanism for automatically locking said type actions against printing movement, a space key, a train of operating connections from 20 the space key for actuating said escapement mechanism, and automatically operating means controlled by the line lock mechanism for rendering the space key ineffective on the escapement mechanism.

25 3. In a typewriting machine, the combination of a carriage, escapement mechanism therefor, type actions, a universal bar controlling said escapement mechanism and controlled by said type actions, line lock 30 mechanism for automatically locking said universal bar against operation when the carriage reaches the end of a line, a space key, operative connections between said space 35 key and universal bar, and means controlled by said line lock mechanism for automatically breaking the connections between the space key and universal bar when the line lock mechanism functions to lock the universal 40 bar.

45 4. In a typewriting machine, the combination of a carriage, escapement mechanism therefor, type actions, a space key, a member through which the escapement mechanism is controlled from the type actions and also 50 from the space key, and means for automatically locking said member when the carriage reaches the end of a line and for simultaneously rendering the space key incapable of acting on said member.

55 5. In a typewriting machine, the combination of a carriage, escapement mechanism therefor, type actions including key actuated type bars, a universal bar for the escapement mechanism actuated by said type bars, a space key, operative connections from said space key to said universal bar, and means for automatically locking said universal bar when the carriage reaches the end of a line 60 and for simultaneously rendering the space key incapable of acting on said universal bar.

65 6. In a typewriting machine, the combination of a carriage, escapement mechanism therefor, type actions including key actuated

type bars, a universal bar for the escapement mechanism actuated by said type bars, a space key, operative connections from said space key to said universal bar including a trip-off device that automatically breaks said connections during the depression of the space key, and means for automatically locking said universal bar when the carriage reaches the end of a line and for simultaneously moving said trip-off device to and for holding it 75 in ineffective position as long as the universal bar remains locked.

7. In a typewriting machine, the combination of a carriage; escapement mechanism therefor; the space key; connections between said space key and escapement mechanism for controlling the operation of the latter, said connections including a trip-off device that automatically breaks said connections during each depression of said key and after an actuation of said escapement mechanism; and automatically operating means for moving said trip-off device to and for holding it in ineffective position when the carriage reaches the end of a line and thus breaking the connections between said space key and the escapement mechanism.

8. In a typewriting machine, the combination of a carriage; escapement mechanism therefor; a key; connections between said key and escapement mechanism for controlling the operation of the latter, said connections including a key actuated lever, an angular trip-off lever carried thereby and pivoted thereon, a spring acting on said trip-off lever, an actuated member with which one arm of the angular trip-off lever is adapted to coat, and a fixed stop interposed in the path of the other arm of said angular trip-off lever; and means for automatically moving said angular trip-off lever out of cooperative relation with said actuated member when the carriage reaches the end of a line.

9. In a typewriting machine, the combination of a carriage; escapement mechanism therefor; means for actuating said escapement mechanism including a space key actuated lever, a trip-off lever carried by said space key actuated lever, an actuated part operated by said trip-off lever and from which the trip-off lever is released before the space key actuated lever completes its movement and after the said actuated part has been operated thereby to actuate the escapement mechanism, a spring for said trip-off lever, cushioning means that noiselessly limits the motion of the trip-off lever under the action of said spring, and a stop fixed in the path of the trip-off lever and which releases it from said actuated part; and means for automatically moving said cushioning means when the carriage reaches the end of a line to shift said trip-off lever to and hold it in a position where it is ineffective on said actuated part.

10. In a typewriting machine, the combi-

nation of a carriage; escapement mechanism therefor; means for actuating said escapement mechanism including a universal bar, a key actuated lever, a trip-off lever carried by said key actuated lever and cooperative with said universal bar and from which the trip-off lever is released before the key actuated lever completes its movement; and automatically operating means for locking said universal bar and for simultaneously shifting said trip-off lever out of cooperative relation therewith when the carriage reaches the end of a line.

11. In a typewriting machine, the combination of a carriage; escapement mechanism therefor; and means for actuating said escapement mechanism including a universal bar, a key actuated lever, a trip-off lever carried by said key actuated lever and cooperative with said universal bar and from which the trip-off lever is released before the key actuated lever completes its movement, a spring for returning the trip-off lever, a cushion stop for noiselessly arresting the return of said trip-off lever, and a stop in the path of said trip-off lever to move it against the force of said spring and trip it off the universal bar.

12. In a typewriting machine, the combination of a carriage; escapement mechanism therefor; means for actuating said escapement mechanism including a universal bar, a key actuated lever, a trip-off lever carried by said key actuated lever and cooperative with said universal bar and from which the trip-off lever is released before the key actuated lever completes its movement, a spring for returning the trip-off lever, a cushion stop for noiselessly arresting the return of said trip-off lever, and a stop in the path of said trip-off lever to move it against the force of said spring and trip it off the universal bar; and automatically operating means for locking said universal bar and for simultaneously shifting said cushion stop and thereby move the trip-off lever out of cooperative relation with the universal bar when the carriage reaches the end of a line.

13. In a typewriting machine, the combination of a carriage, escapement mechanism therefor, a substantially horizontally disposed universal bar for actuating said escapement mechanism, a series of type bars that coact directly with and actuate said universal bar, line lock mechanism including a member that coacts directly with said universal bar and locks it against operating movement when the carriage reaches the end of a line, a space key, connections between said space key and universal bar including a trip-off device, and means controlled by said line lock lever for shifting said trip-off device to ineffective position when the line lock lever is shifted to lock the universal bar.

14. In a typewriting machine, the combi-

nation of a carriage, escapement mechanism therefor, a substantially horizontally disposed universal bar for actuating said escapement mechanism, a series of type bars that coact directly with and actuate said universal bar, line lock mechanism including a member that coacts directly with said universal bar, and locks it against operating movement when the carriage reaches the end of a line, a space key, connections between said space key and universal bar including a trip-off device, a spring for returning said trip-off device, and a cushion stop for noiselessly arresting the return movement of said trip-off device.

15. In a typewriting machine, the combination of a carriage, escapement mechanism therefor, a substantially horizontally disposed universal bar for actuating said escapement mechanism, a series of type bars that coact directly with and actuate said universal bar, line lock mechanism including a member that coacts directly with said universal bar and locks it against operating movement when the carriage reaches the end of a line, a space key, connections between said space key and universal bar including a trip-off device, a spring for returning said trip-off device, a cushion stop for noiselessly arresting the return movement of said trip-off device, and means controlled by said line lock lever for shifting said cushion stop and thereby moving said trip-off device to and holding it in ineffective position as long as the line lock lever is held in its effective position.

16. The combination of a carriage, escapement mechanism therefor, printing keys, means controlled thereby for actuating said escapement mechanism, line lock mechanism for locking the printing keys against printing actuation when the end of a line is reached, a space key, an independent train of actuating connections between said space key and the escapement mechanism, and means for breaking said train of actuating connections when the line lock mechanism is actuated, whereby the space key is rendered ineffective on the escapement when the printing keys are locked against printing actuation at the end of a line.

17. The combination of a carriage, escapement mechanism therefor, a space key, operating connections from said space key to the escapement mechanism including a trip that is automatically released at each operation before the spacing key reaches the limit of its depression and after the escapement has been actuated, a cushion stop with which the trip coacts to noiselessly limit its movement in one direction during the operation of the space key, and automatically operating means for shifting said cushion stop and thereby render said trip ineffective to actuate the escapement mechanism.

18. In a typewriting machine, the combi-

nation of printing keys, type bars controlled thereby, a carriage, escapement mechanism therefor, a space key, connections between said space key and escapement mechanism for controlling the operation of the latter, said connections including a trip-off device that automatically breaks said connections during each depression of said space key and after an actuation of said escapement mechanism, whereby any printing key may be actuated to operate its type bar and effect a letter space feed of the carriage even in the event that the space key is held depressed, and automatically operating means for moving said trip-off device to and holding it in a position where it is ineffective to actuate the escapement mechanism when the carriage reaches the end of a line.

19. In a typewriting machine, the combination of printing keys, type bars controlled thereby, a carriage, escapement mechanism therefor, a space key, a trip-off lever actuated by said space key, an actuated part for controlling the escapement mechanism operated by said trip-off lever and from which the trip-off lever is released before the space key completes its movement and after said actuated part has been operated by the trip-off lever to actuate the escapement mechanism, a spring for said trip-off lever, cushioning means that noiselessly limits the motion of the trip-off lever under the action of said spring, whereby any of said printing keys may be actuated to operate its type bar and effect a letter space feed of the carriage even in the event that the space key is held depressed, and means for automatically moving said cushioning means when the carriage reaches the end of a line in order to shift said trip-off lever to and hold it in a position where it is ineffective on said actuated part.

40 Signed at Stamford, in the county of Fairfield and State of Connecticut, this 4th day of June, A. D. 1929.

45 GEORGE G. GOING.
